UNITED STATES PATENT OFFICE.

FRANK D. WHEELER, OF DETROIT, MICHIGAN, ASSIGNOR TO THE HAUGHTON ELEVATOR & MACHINE COMPANY, OF TOLEDO, OHIO.

ELEVATOR-DOOR LOCK.

Application filed December 29, 1919. Serial No. 347,941.

To all whom it may concern:

Be it known that I, FRANK D. WHEELER, a citizen of the United States of America, residing at Detroit, Wayne County, Michigan, have invented a new and useful Elevator-Door Lock, of which the following is a specification.

This invention relates to safety devices in connection with power apparatus.

10 This invention has utility when incorporated as an electric interlock for landing doors of elevators.

Referring to the drawings:

15 Fig. 1 is a wiring diagram of an embodiment of the invention in connection with an alternating current motor driven elevator;

Fig. 2 is a detail view of one of the landing doors of the elevator with the safety device of this invention incorporated therewith, the door being shown in open position;

20 Fig. 3 is a perspective view of the lock and its key;

Fig. 4 is a bottom plan view of the lock with the cover removed; and

25 Fig. 5 is a section on the line V—V, Fig. 4.

Elevator shaft 1 is provided with a plurality of landings 2 for elevator car 3 normally operable by cable 4 extending to 30 counterweight 5. This elevator may be driven by an electric motor 6, the operation of which is determined by a controller 7 in the car 3 through control lines from main switch 8 and up switch 9 and down switch 35 10 receiving supply of power current from power lines 11, 12, 13. From the power line 13 extends branch line 14 through safety devices including the invention of this disclosure herein shown as terminals 15 40 through contacts 16 as a bridge to terminals 17 at each landing. Accordingly, when this terminal 16 is closing the connection between the contacts 15, 17, this safety device switch is closed and line 14 may be effective 45 for energizing the main switch 8 when the controller 7 is shifted.

This switch contact 16 is herein spaced by insulation 18 (Fig. 4) from drum 19 having a key hole or slot 20 therein. This drum 19 is fastened by screw 21 in position and may have a torsion spring 22 in a recess 23 (Fig. 5) in the bottom thereof normally urging this member toward open position with the contact 16 against fixed stop 24. The respective terminals are nor-

mally urged by compression helical springs 25 toward the drum 19 but are precluded from contacting such drum by keys 26. These terminals 15, 17, are mounted in terminal blocks 27 carrying terminal screws 28 to which may be connected line wire 14 in its coming into and going from lock or box 29 through an end opening and conduit 30.

The terminal blocks 27 are mounted on insulation block 31 in the housing 29. The lock housing or box 29 is provided with a plate or cover 32 having thereon projecting guide portions 33 as directing means for head 34 of locking bar or key 35, carried by guides 36, for rotation as to its mounting on door 37 at a landing 2 of shaft 1. Accordingly, this landing door 37 in moving toward closed position at landing 2 of shaft 1 on its hinges 38 has its head 34 of the key of the lock bolt 35 ride into the guide ways 33 for entrance into the lock of the housing 29. An upward push of this bar 35 into the lock 29 inserts this bar 35 into the key-hole 20 of drum 19. A 50 rotation of the bar 35 to change the direction of its projecting handle from a straight out position to a position in parallel with the door throws the drum 19 a ninety degree turn to bring its contact 16 into engagement with the pair of terminals 15, 17, thereby closing this switch of the safety device to permit, when the door of the landing is closed, an operation of the controller 7 in the elevator car 3 so that this car may be 55 actuated by motor 6. With any landing door 37 open, its switch contact 16 would be open and it would be impossible to get power to main switch 8, therefore it would be impossible to operate the controller 7 to move the car 3 from motor 6.

With the elevator car 3 at a landing 2 and landing door 37 open, such door 37 is swung on its hinges 38 to closed position. When so closed, the bar or key 35 is thrust 60 upwardly into the keyhole 20 as directed by the guide portions 33. Turning of the key thus inserted, swings the drum 19 to bring contact 16 between the terminals 15, 17. The operator in the car 3, may now 65 shift the controller 7 to the left, swinging the terminal carrying lower portion thereof to the right. There results first an energizing of the main switch 8, and then of the direction switch 9, when the brake is 70

- released and the motor 6 operates to cause the car 3 to travel upward. As the next landing or desired landing for a stop is reached, the controller 7 is swung to central or neutral position, at once de-energizing switches 8, 9, allowing the brake to set and the motor 6 to be held in stopped position. The operator then swings the key or bar 35 at such floor landing door, 5 so that the key may slide down out of the lock. The rotation of the key before dropping downward, turns the drum 19 to open line 14 to the main switch 9, because contact 16 has been moved away from the terminals 15, 17. With this break in the circuit to the main switch 9, all attempt to shift the car 3 by operation of the controller 7 is futile. With the combined door locking key and bolt 35 in dropped or door 10 unlocking position, the door 37 may be swung open on its hinges 38, for taking on a load or taking off a load at such landing.
- What is claimed and it is desired to secure by Letters Patent is:
- 25 1. A power drive apparatus, a control therefor, a door, a lock for the door, a housing for the lock, a switch in the housing to preclude control operation when the door is open, and means independent of the housing carried by the door and manually movable to enter the housing when the door is closed and then movable to operate the switch to render said control operative, said means in position for operating the switch 30 being held by the housing against direct removal therefrom.
2. A power drive apparatus, a control therefor, a door, a lock for the door, a housing for the lock, and a key bolt for the lock independent of the housing carried by the door, and manually operable for withdrawal from the housing to permit opening of the door, said key bolt in its operation for withdrawal rendering the control ineffective, said housing being provided with means holding the bolt from direct removal therefrom when the bolt is in position to render the control effective.
3. An elevator, an electric motor drive 40 therefor, a controller for the elevator, a shaft in which the elevator is movable, landings along said shaft, a landing door at one of said landings, a lock for the door, a housing for the lock, a key exterior of the housing operable when the door is closed to enter the housing to lock the door, and a switch for the controller located in said housing and coacting when closed to hold the key from withdrawal from the housing.
4. An elevator shaft having landings, an elevator movable in said shaft, landing doors, driving means for the elevator, a control for the driving means, a lock for a landing door, a housing for the lock, and 45 means exterior of the housing operable to enter the housing only at closed position of the door to permit the control to become effective, said housing holding the means from direct removal when the means is in position to permit the control to become effective.
5. An elevator shaft having a landing, a door at said landing, an elevator in the shaft movable to said landing, a power drive for the elevator, an electric control 75 for the drive, a lock for the landing door effective for locking independently of the position of the elevator, said lock including a switch for the control, a housing for the lock and switch, and a rotatable key exterior of the housing operable to enter the housing and there rotatable to operate said switch.
6. An elevator shaft having a plurality of landings, a door at each landing, an elevator in the shaft, an electric drive for moving the elevator between the landings, a controller on the elevator, a control line therefrom for the drive, a lock for each landing door effective for locking independently of the position of the elevator, each lock including a switch in the control line, a housing for each lock and switch, and a rotatable key for each door exterior of the housing reciprocable thereinto to lock the door and there rotatable to close the switch.
7. An elevator shaft having a plurality of landings, a door at each landing, an elevator in the shaft, an electric drive for moving the elevator between the landings, an electric control line for the drive, a lock for each landing door, effective for locking independently of the position of the elevator, each lock including a switch in the control line, a reciprocable and rotatable locking bolt key carried by each door, said key reciprocable to door locking position and there rotatable to switch closing position, and a controller to which said control line extends and which controller is rendered effective for actuating the drive upon closing of such switch.
8. An elevator landing door, a bolt carried thereby, a housing into which the bolt may enter at closed position of the door to hold the door from shifting, said bolt being rotatable in the housing independently of releasing the door, and a door interlock switch closed by rotation of the bolt away from housing entering position.
9. An elevator landing door interlock device embodying a housing, a key bolt for the housing registering for entering the housing at closed position of the door, and a switch in the housing closed by rotation of the bolt away from housing entering position.
- In witness whereof I affix my signature.
FRANK D. WHEELER.
